UNITED STATES PATENT OFFICE.

HORACE C. WILCOX, OF WEST MERIDEN, CONNECTICUT, ASSIGNOR TO THE MERIDEN BRITANNIA COMPANY, OF SAME PLACE.

DESIGN FOR CALL-BELL.

Specification forming part of Design No. 5,195, dated August 8, 1871.

To all whom it may concern:

Be it known that I, HORACE C. WILCOX, of West Meriden, in the county of New Haven and State of Connecticut, have invented a new Design for Call-Bell; and I do hereby declare the following, when taken in connection with the accompanying photographic illustration, to be a full, clear, and exact description of the same, and which said illustration constitutes part of this specification and represents a side view.

This invention relates to a design for that class of bells known to the trade as gong-bells, and which are operated by a spindle passing down through the center of the gong to strike the hammer. Heretofore the base or neck upon the top of the bell through which the spindle passes has been constructed without regard to design or character; and my invention relates to this particular part of the bell; and consists in the arrangement of a bird upon the top of the bell in

a "fluttering" position, the spindle passing down through the back between the wings.

The bell and its base, being no part of this design, may be of any of the well-known forms, or such as may be required by the trade or taste of the manufacturer.

On the top of the bell, at the center, I arrange a bird standing with the wings and body in the position of fluttering, the spindle and head of the spindle coming up through the back between the wings, all as fully shown in the accompanying photographic illustration.

I claim as my invention—

The design for call-bell, as shown in the accompanying photographic illustration, and as herein described.

HORACE C. WILCOX.
